ELECTROACOUSTIC TRANSDUCER

Richard W. Samsel, Schenectady, N. Y., assignor to General Electric Company, a corporation of New York

Application September 10, 1948, Serial No. 48,656

1 Claim. (Cl. 340—10)

My invention relates to electroacoustic transducers and more particularly to underwater sound transducers utilizing piezoelectric crystals wherein a lens of sound transmitting material is disposed between the crystal element or elements and the water medium into which the sound is directed or from which the sound is received.

An object of my invention is to provide an improved wide beam angle electroacoustic transducer.

A more specific object is to provide an improved unitary transducer incorporating a sound lens to determine the beam width through which sound is to be directed or is to be received.

A further specific object is to provide a wide beam angle piezoelectric crystal transducer comprising a flat supporting surface for the crystal elements.

An additional object is to minimize damping effects on the crystal elements of a piezoelectric crystal transducer.

The novel features which I believe to be characteristic of my invention are set forth with particularity in the appended claim. My invention itself, however, both as to its organization and method of operation, together with further objects and advantages thereof may best be understood by reference to the following description taken in connection with the accompanying drawing in which Fig. 1 is a back view, partially cut away, and Fig. 2 is a cross sectional side view of a transducer according to my invention; Figs. 3 and 4 are enlarged detail sectional views of portions of the transducer; and Fig. 5 is a chart showing typical operational characteristics of a transducer according to my invention.

Referring to Figs. 1 and 2 of the drawings, a plurality of piezoelectric crystal elements 1 are shown arranged in a regular pattern across the back surface of a flat circular disc 2 of sound-transmitting material such as a methyl methacrylate plastic. The crystals may be L-cut Rochelle salt crystals each having a separate conductive foil electrode of tin or other soft metal substantially coextensive with each major face of each crystal element. Foil electrodes 3 covering the exposed or back major face of each crystal are visible in Fig. 1, and the position of electrodes 3 as well as of electrodes 4 covering the front major face of each crystal is shown in Figs. 2, 3 and 4. The foil electrodes are preferably applied to both major faces of each crystal by first covering the face with a thin film or coating of liquid cement and then laying the foil across the face and rubbing the exposed surface of the foil with a smooth, rounded object.

The crystal elements with electrodes in place are cemented to the back surface of disc 2, preferably with a rubber cement with ethylene dichloride solvent. The end portion of a connecting foil tab 5 is interposed at one edge of each crystal element to provide an electrical connection to one electrode of each. Tabs 5 are shown in Figs. 1 and 2, but in greater detail in Fig. 3, wherein tab 5 is arranged with end portion 6 underlying crystal element 1 and disposed between electrode 4 and disc 2.

2

While electrodes 3 and 4 and the end portion 6 of tab 5 are shown in Fig. 3 as having substantial thickness, in an actual device the foil is very thin, of the order of one-thousandth of an inch or less, and the surfaces of the

5 crystal and disc are very close together. Since the crystal electrode 4 is cemented to the crystal face, and cemented additionally to the flat back face of disc 2, the crystal is held firmly against the disc and the thin layers or films of cement and the foil do not substantially affect 10 the transmission of the mechanical vibration of the crystal into the disc 2. As shown in Fig. 3, tab 5 extends from the area of contact with electrode 4 between adjacent crystal elements 1 to a free end. Slips 7 of an 15 insulating material, such as a synthetic resin, are arranged on either side of tab 5 to insure against accidental contact with electrode 3 and to give support to tab 5. The free ends of tabs 5, as shown in Figs. 1 and 2, are wrapped about and preferably soldered with a low temperature metal solder to bus members 8 which are in turn 20 connected to and supported by a peripheral bus member 9.

To provide connections to the exposed electrodes 3, as shown in Figs. 1, 2 and 4, narrow strips of foil 10 are cemented to the electrodes 3 on the back faces of rows

25 of the crystals 1 and are connected by wrapping about and soldering to a peripheral bus member 11, thus serving to connect all the back electrodes 3 of all of the crystals together and to the bus member 11. Peripheral members 9 and 11 are supported by insulating blocks 12

30 of synthetic resin or plastic and are disposed in holes drilled through the blocks. In order that soldering and consequent heating of copper bus members 9 and 11 will not melt the blocks 12, small heat resistant sleeves

35 13 of fiber or other material line each of the drilled holes in the blocks. Bus members 9 and 11 of the two bus systems terminate in a suitable dual contact receptacle 14 for connecting all of electrodes 3 to one terminal of an external apparatus and all of electrodes 4 to another terminal.

40 The external apparatus may be, for example, an underwater sound transmitter between the output terminals of which appears an exciting voltage for the crystal transducer, or it may be a receiver with input terminals arranged to receive the voltages produced across the pairs of electrodes of each crystal in response to received sound waves.

The complete transducer unit comprises the disc 2, a hollow cylindrical member 15, a back cover plate 16 and a sound lens 17. These parts may be assembled by

50 various methods, but the assembly is probably most conveniently accomplished by casting the lens 17, which is preferably of plastic material, and placing the disc 2 against the flat face thereof prior to hardening of the lens whereby these two members will be bonded together.

55 The cylindrical housing member 15 may be cemented peripherally around disc 2, and to the peripheral back flat face portion of lens 17. The back cover plate 16 is cemented and bolted in place with a gasket 18 and bolts 19 cooperating with the housing. An inwardly extending flange 20 assists in maintaining a tight joint, preventing any leakage adjacent bolts 19.

60 Housing member 15, and cover plate 16, may both be of methyl methacrylate. Flange 20, shown as part of housing member 15, may be a separate ring member cemented to the housing. Gasket 18 is preferably of rubber.

65 Many of the parts mentioned are identified in each of several of the figures to assist in an understanding of the invention. As shown in Fig. 1, connecting receptacle 14 is so mounted as to provide an air and water tight seal with the housing member 15, and the crystal elements are thus enclosed in a sealed chamber. The atmosphere in

the chamber may be air or any desired gas. For convenience in mounting the complete transducer assembly, drilled and tapped blocks or lugs 21 are cemented to the cover plate as shown in Fig. 2.

Lens 17 is preferably formed of a polystyrene base plastic or synthetic resin material, and according to the invention has an index of refraction for sound less than the index for the medium in which it is intended for use. The exposed front face of the lens is preferably spherical.

The transmitter operating, alternating current electrical energy of, for instance, several hundred kilocycles is provided between bus members 9 and 11 from suitable external apparatus through the connector 14 to excite the vibratile elements 1. The vibration of these elements is transmitted through disc 2 and lens 17 to the external medium, which may be water, and leaves the outer curved face of the lens as a broad beam centered about the lens axis. Since the back face of each element is in contact only with air, there is very little damping of the elements, and the transducer has a high efficiency. The beam is broad with the spherical lens as shown and described because the speed of sound or compressional waves through the material comprising the lens is greater than the speed in water. Fig. 5 is a polar plot diagram showing the typical relative intensities of the transmitted beam in different directions from the face of the transducer, the beam pattern being centered about the lens axis. The transducer unit is identified in this figure by reference numeral 22. When used for reception, the sensitivity of the transducer is also in accord with this diagram. It will be understood that this diagram is exemplary and approximate only since the shape of the beam differs for different frequencies and in accord with differences in other conditions.

When used for reception, the elements 1 may be excited to generate electrical energy by compressional waves approaching the lens from directions within a wide angle as measured from the lens axis. The energy thus generated is collected from the crystal element electrodes and appears as a signal between busses 9 and 11.

The transducer is particularly adapted to underwater object locating and may serve as a transmitter, as a receiver, or as transmitter and receiver. It may be desired, for instance, to energize the elements to transmit compressional waves at a frequency of, for instance, several hundred kilocycles for an interval of time, to then disconnect the bus system 9, 11 from the external signal generator and connect the busses to cathode ray display apparatus arranged to indicate the reception of echoes of the previously transmitted frequency received after reflection thereof from submerged objects. In such applications the transducer may be mounted below the water

line external to the hull of a vessel, within a suitable housing if desired, and arranged with mounting means for orienting the transducer in a desired direction and, conveniently, including means for changing the orientation. The signal generating and display apparatus may be arranged within the hull with connections to the busses 9, 11 extending through the hull.

While I have shown only certain preferred embodiments of my invention by way of illustration, modifications will occur to those skilled in the art and I therefore wish to have it understood that I intend, in the appended claim, to cover all such modifications as fall within the true spirit and scope of my invention.

What I claim as new and desire to secure by Letters Patent of the United States is:

An electroacoustic transducer comprising a circular solid plastic lens member with a convex front face and planar back face, a solid plastic disc member of substantially the same diameter as said lens firmly affixed by one face to said back face, a plurality of piezoelectric crystal elements each with two electrodes covering opposite major faces thereof, each of said elements being closely spaced and firmly affixed to the other face of said disc at an electrode covered major face of each element, said plurality of elements being substantially coextensive with said disk, two electrical conductive bus systems interconnecting respective electrodes of said elements in a polarity such that in-phase vibration of said crystal elements corresponds to a voltage between said bus systems of a phase of predetermined relation to said vibration, one of said bus systems having insulated conductors passing between adjacently mounted ones of said elements, each conductor making connection to the electrode covering the affixed face of a different element, and means forming a sealed casing for said elements, said last means comprising at least one of said members, and a conductive portion of each of said bus systems sealed through said last means to provide external connections to said electrodes.
